(57) **CLAIM**

The ornamental design for a vacuum cleaner, as shown and described.

DESCRIPTION

FIG. 1 is a top, right-side, and front view of a vacuum cleaner, showing the new design.

FIG. 2 is a front elevation view of the vacuum cleaner.

FIG. 3 is a right-side elevation view of the vacuum cleaner.

FIG. 4 is a top plan view of the vacuum cleaner.

FIG. 5 is a left-side elevation view of the vacuum cleaner.

FIG. 6 is a rear elevation view of the vacuum cleaner.

FIG. 7 is a top, right-side and front perspective view thereof, the only difference resides in the broken lines which show a different vacuum cleaner base.

FIG. 8 is a front elevation view of FIG. 7;

FIG. 9 is a right-side elevation view of FIG. 7;

FIG. 10 is a top plan view of FIG. 7;

FIG. 11 is a left-side elevation view of FIG. 7; and,

FIG. 12 is a rear elevation view of FIG. 7.

The vacuum cleaner shown in broken lines forms no part of the claimed design.
